ATTORNEY

UNITED STATES PATENT OFFICE.

WILLIAM A. HARTLINE, OF PENNS GROVE, NEW JERSEY.

ATTACHMENT FOR PENS.

1,268,970.

Specification of Letters Patent. Patented June 11, 1918.

Application filed November 22, 1917. Serial No. 203,409.

To all whom it may concern:

Be it known that I, WILLIAM A. HARTLINE, a citizen of the United States, residing at Penns Grove, in the county of Salem and 5 State of New Jersey, have invented certain new and useful Improvements in Attachments for Pens, of which the following is a specification.

This invention relates to attachments for 10 pens, and more particularly to a device adapted to be mounted on a pen and to support a blotter and other members which are normally used in connection with correspondence.

15 One of the main objects of the invention is to provide an attachment of the character stated of simple construction and operation which may be quickly and easily produced at very small cost. A further object 20 is to provide a casing having means for detachably securing the same on a penholder, this casing being provided with a blotter projecting from the same so as to be readily available for use. A further object is to 25 provide a casing having cutting means for opening envelopes and also provided with a device for holding an ink eraser. Further objects will appear from the detailed description.

30 In the drawings:

Figure 1 is a front view of an attachment constructed in accordance with my invention as applied,

35 Fig. 2 is a back view of the same, the envelop opening device being shown projecting from its casing,

Fig. 3 is a section taken substantially on line 3—3 of Fig. 1,

Fig. 4 is a section on line 4—4 of Fig. 1,

40 Fig. 5 is a top plan view of the device as illustrated in Fig. 1,

Fig. 6 is a front view of a modified form of the device in open position,

Fig. 7 is a fragmentary section taken substantially on line 7—7 of Fig. 6,

Fig. 8 is an underneath view of another modified form of attachment,

Fig. 9 is a top plan or edge view of the same,

50 Fig. 10 is a section taken substantially on line 10—10 of Fig. 8,

Fig. 11 is an underneath view of another modified form,

Fig. 12 is a section on line 12—12 of 55 Fig. 11,

Fig. 13 is a section on line 13—13 of Fig. 11,

Fig. 14 is a view similar to Fig. 11 the upper jaw of the cutting member being removed, and

60 Figs. 15 to 24 are detailed views of modified forms of cutting members and the blades therefor.

In constructing my attachment, I provide a sheet metal casing 1 which is of frusto-cylindrical shape. This casing is formed with the body 2 having the upwardly directed flange 3, and the cover 4 which fits snugly within this flange. This cover is provided, at its outer edge, with a sheet 70 metal collar 5 secured thereto provided with an inwardly directed peripheral flange 6 which forms a retaining collar for a glass covering or crystal 7. The collar 5 forms a cylindrical recess above the top 8 of the 75 cover which is adapted to receive a photograph 10 inserted beneath the crystal 7, or card with advertising matter printed thereon. It will be evident, of course, that, if preferred, the under face of the crystal 7 80 could be silvered to produce a convexed mirror.

A pin 11 is secured in the bottom 12 of body 2 of the casing and extends to within a short distance of the inner face of the 85 top of the cover. This pin is adapted to fit snugly into a bore provided at the center of a blotting disk 13 which may be formed of blotting paper, or other suitable material.

This blotting disk corresponds approximately in thickness to the distance between the top 8 and bottom 12 of the casing, and is of approximately the same diameter as the casing so as to normally project through and beyond the flattened peripheral 90 portion 14 of the same, as in Figs. 1 and 2 of the drawings. A cylindrical sheet metal securing member 15 is secured on the back of casing 1, this member being extended and

95 bent to provide an integral housing 16 which is secured to the back of the casing. Member 15 is adapted to snugly receive the upper end portion of pen 17 so as to detachably secure the casing on the pen. As will be

100 noted more clearly from Fig. 2 of the drawings, the securing member 16 extends in parallelism with the flattened peripheral portion 14 of the casing, so that the blotter disk 13 projects laterally of the pen. In

105 using this device, after a line has been writ- 110

ten, the disk 13 may be rolled over the same, the pen 17 being used as a handle for holding the casing, so as to blot or dry the ink. By disposing the holding securing member 15 in the manner specified, interference of the pen with the use of the device for blotting purposes is eliminated.

At the opposite side of the casing from the flattened portion 14, and disposed at a right angle thereto, is secured a rectangular eraser holding frame 18 formed by bending from a strip of sheet metal and secured to the back of the casing. This frame is adapted to securely hold an ink eraser 19. As will be noted, this eraser is so disposed as to project laterally of the pen 17 at the opposite side of the casing from the flattened portion 14 thereof, so that either the blotter or the eraser may be readily used, the use of either one of these members not being in any way interfered with by the pen 17.

When the blotter disk 13 is not being used, the cover 4, which fits snugly within the body of the casing, may be turned so as to bring the peripheral flange thereof in front of the portion of disk 13 which normally projects through the side of the casing, thus covering the disk so as to protect the same against injury. When it is desired to use the blotter, after the pen and the attachment carried thereby has been removed from the pocket, the casing cover will be turned into such position as to bring the flattened peripheral portion thereof into register with the flattened peripheral portion of the body of the casing, as illustrated in the drawings. When the cover has been thus turned, the blotting disk will project through and beyond the flattened peripheral portion 40 of the casing, as specified.

The housing 16 secured on the bottom of the casing is provided with an inner elongated arm 20 which is soldered to the casing. This arm is turned up for a short distance at each lateral edge to provide a short U-guide 21 at each side of the arm. These guides receive the inner arm 22 of a resilient U-member 23 which is thus slidably mounted on the inner arm of the housing. The outer arm 24 of this U-member is turned inward at right angles and shaped to provide a V-shaped cutting point 25. A rectangular gage member 26 is secured to the outer face of the inner arm 22 of the U-member and is of such length as to permit sufficient inward movement of the outer arm 24 to bring the cutting point 25 between the outwardly directed flange 27 formed at the outer end of inner arm 22 of the U-member and the flange 28 formed at the outer end of the rectangular gage member 26. When this U-shaped cutting member is in its retracted position within the housing 16, the outer arm 24 will be held in depressed position by the outer wall of the housing, as shown in Fig. 4 of

the drawings. When the cutting member is moved into its outermost position, as shown in Fig. 2 the outer arm thereof will be released so as to permit raising of the same facilitating insertion of the edge portion of an envelop to be opened between the cutting blade 25 and the spaced vertical flanges 27 and 28. When the edge portion of an envelop has been inserted beneath the cutting blade, the outer jaw 24 may then be forced downward so as to force the cutting blade into the envelop, after which the envelop may be readily opened by moving the casing longitudinally of the same. The U-guide members 21 at each side of the extended arm or base 20 of the housing 16, while permitting movement of the cutting member in either direction, serve to positively limit the outward movement of this member and to effectually prevent its complete removal from the casing. After being used in the manner described, the cutting member may be readily pushed back into the housing 16, this member having sufficient resiliency to hold the outer arm 24 thereof in close frictional engagement with the inner face of the outer wall of the housing so as to prevent any looseness or accidental removal of the cutting member from the housing.

A device constructed in the manner set forth can be made practically entirely from sheet metal and may, therefore, be produced at relatively small cost. In addition, in practice the device may be made comparatively small and, due to its light construction, is well adapted to be mounted on a pen in the manner set forth and carried in a person's pocket with the pen. By this arrangement I insure that blotting and erasing means will at all times be readily available to a person using this device in conjunction with a pen, as well as means for opening envelops and similar containers relating to correspondence.

In Fig. 6 of the drawings, I have shown a modified form of container which is the same as that above described except that the body 30 and cover 31 are hingedly secured together as at 32, instead of being telescopically connected. This form of a device is identical with that previously described in all other respects and, need not, be further described in detail.

In Figs. 8, 9 and 10 I have shown still another modified form in which the cutting device described is replaced by U-member 33 formed from a continuous piece of metal the inner arm 39 of which is soldered to the back of the casing, the outer arm 34 being provided at its free or outer end with the spaced transverse arms 35 and 36 between which is secured the blade 37, this blade being so positioned as to fit into a slot 38 through the bottom of the casing when depressed. The outer end of the inner arm 39

of member 33 is turned upward at a right angle to provide a limiting finger 40 which acts to positively limit the inward or downward movement of the outer arm 34 in the same manner as the outwardly directed arm of the member 26 in Fig. 4 limits the inward movement of the outer arm of the cutting member. In all other respects, this modified form is similar to that illustrated in Figs. 10 1 to 5 inclusive.

In the modified form shown in Figs. 11 to 14 inclusive the cutting member is formed from an arm 41 secured to the bottom of the casing and turned out at a right angle to provide a limiting finger 42 adapted to engage the outer arm 43 which is pivotally mounted on a pintle 44 passed through the aligned pairs of ears 45 and 46 carried by the arms 43 and 41 respectively. Outer arm 43 20 extends beyond the limiting finger 42 and is turned inward at a right angle and sharpened to provide a cutting blade 47 adapted to fit into a slot 48 through the bottom of the casing when the arm is depressed. Arm 25 43 is normally held in inoperative or depressed position by a wire spring 49 secured to the inner arm 41, the outer arm of this spring normally pressing against the underface of arm 43 in rear of the pintle 44.

The cutting member illustrated in Fig. 15 is formed from a continuous piece of sheet metal bent into substantially U-shape. This member has the inner arm 50 and the outer arm 52. The inner arm is cut to provide 35 a central tab which is turned up at a right angle to the body of the arm to provide an outwardly directed limiting finger 53. This arm is further provided, at its outer end, with the two spaced upwardly directed 40 guide members or flanges 54 and 55 and the slot 56 intermediate the same. These members are adapted to receive between them the cutting blade 57 formed at the outer end of the upper arm 52. A set screw 58 is threaded 45 through the upper arm 52 and adapted to engage the bottom of the casing so as to positively limit downward or inward movement of the blade 57. This set screw is supplemental to the limiting finger 53, the object 50 being to provide means for permitting adjustment of the forward movement of the cutting blade within certain limits. The form of cutting device shown in Fig. 16 resembles closely that illustrated in Fig. 15, 55 except that the blade 59 instead of being formed integral with the outer arm 52a is secured between the two depending flanges 60 and 61 carried by this arm. In the modified form shown in Fig. 17, the limiting finger 60 is omitted, the downward movement of the outer arm 62 being regulated by the set screw 63 threaded through the same. Arm 62 is turned downward at an obtuse angle at its outer end to provide a flange 64. This 65 flange is provided with a threaded bore

which receives a securing screw 65 threaded through a holding frame 66 and the blade 67 carried thereby. This frame 66 fits about the side and top edges of the blade so as to support and brace the same, and is also used as a holding member for the blade when being sharpened. In addition, by this construction the blade may be quickly and easily removed from, or secured to, the upper arm 62 of the cutting member, thus facilitating sharpening or replacing of a blade. This construction will be more readily understood by reference to Figs. 21 and 23 of the drawings, from which it will be seen that the holding frame 66 is shaped so as to fit about the top and side edges of the blade 67, this frame acting to brace and support the blade when secured to the depending flange 64 of arm 62 of the cutting member by means of the screw 65. In the form illustrated in Fig. 18, the cutting blade 68 is secured to the inclined flange 69 at the end of arm 70 by means of a screw 71 inserted through the same and through the blade holding and bracing frame 72. This frame 75 also fits about the side and top edges of the blade so as to brace and reinforce the same. The upper arm 70 of this cutting member is provided with lateral depending ears 73 which are pivotally secured by the pintle 74 to the ears 75 carried by the lower arm 76, this lower arm being provided with the limiting finger 77 and the spaced flanges 78 for receiving the blade 68. A wire spring 79 is secured on the lower arm 76, the free arm of this spring exerting pressure on the underface of upper arm 70 so as to normally force the cutting blade 68 downward. A modification of the form shown in Fig. 18 is illustrated in Fig. 19. In this figure, the 80 limiting finger 77 is replaced by a set screw 81 threaded through the lower arm 82, and the blade 83 is secured by the securing screw 84 between the depending spaced flanges 85 formed on the inner face of the upper arm 86. The arms 81 and 85 are also provided, at the ends thereof remote from the cutting elements, with intermeshing teeth 87 and 88, respectively. A wire spring 88a is mounted 90 about the pintle 89 and acts to normally force the gripping teeth of the arms 81 and 85 together thus providing means for securing this device in a person's pocket by engagement of the gripping teeth with the edge portion of the pocket in the well known manner. When it is desired to cut or open an envelop, the cutting blade 82 may be forced between the spaced members 88 by exerting pressure thereon with the thumb in the manner previously described. The mounting of the blade in this form is more clearly illustrated in Fig. 20 which is an enlarged fragmentary detail. As will be noted, by removing the screw 83, the blade 82 may be quickly and easily removed for 100 105 110 115 120 125 130

sharpening, or to permit the insertion of a new blade.

In Figs. 22 and 24 the blade 90 is of V-shape. This blade fits snugly into a supporting and reinforcing frame 91 having the spaced apertures 92 which receive the securing screws 93. The screws 93 are threaded through apertures 92 and through the alined apertures 94 in the blade and into suitable 10 bores 95 in the depending and inclined flange 96 of the upper arm 97 of the cutting device. The frame 91 acts to support and reinforce the blade, while the screws 93 serve to firmly secure the blade within the 15 frame and to secure the frame to the arm 97, it being understood, of course, that the apertures in the blade, the reinforcing and bracing member 91, and the depending flange 95, are all in alinement when the 20 vice is assembled.

What I claim is:

1. A frusto-cylindrical casing, a blotting disk rotatably mounted therein and projecting through the flattened peripheral portion 25 of the casing, a resilient member secured to the back of the casing and adapted to snugly receive the end portion of a penholder so as to secure the casing on the same, said securing member being extended and bent to 30 form a housing, and a resilient approximately U-shaped cutting member slidably mounted in said housing provided at the

outer end of its outer arm with an inwardly directed cutting blade.

2. A housing, a member carried thereby 35 adapted to snugly receive the end portion of a penholder for securing the housing to the same, and a resilient U-shaped cutting member slidably mounted in said housing for limited movement in either direction and 40 provided with an inwardly directed cutting blade at the outer end of its outer arm.

3. A casing having a flattened peripheral portion, a blotting disk rotatably mounted in the casing and projecting beyond the 45 flattened peripheral portion thereof, and a cover mounted in the casing and having a depending flange fitting into the same, said cover being provided with a flattened peripheral portion adapted to be brought into 50 register with the flattened portion of the casing so as to expose the peripheral portion of the disk, the flange of the cover being adapted to inclose and protect the projecting peripheral portion of the disk when the 55 flattened peripheral portion of said cover is moved out of register with the flattened peripheral portion of the casing.

In testimony whereof I affix my signature in presence of two witnesses.

WILLIAM A. HARTLINE.
